CLAIM

The ornamental design for an LED light, as shown and described.

DESCRIPTION

FIG. 1 is a perspective view of a first embodiment of an LED light showing our new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top elevational view of FIG. 1;

FIG. 7 is a bottom elevational view of FIG. 1;

FIG. 8 is another perspective view of FIG. 1;

FIG. 9 is a perspective view of a second embodiment of an LED light showing our new design;

FIG. 10 is a front elevational view of FIG. 9;

FIG. 11 is a rear elevational view of FIG. 9;

FIG. 12 is a left side elevational view of FIG. 9;

FIG. 13 is a right side elevational view of FIG. 9;

FIG. 14 is a top elevational view of FIG. 9;

FIG. 15 is a bottom elevational view of FIG. 9;

FIG. 16 is another perspective view of FIG. 9;

FIG. 17 is a perspective view of a third embodiment of an LED light showing our new design;

FIG. 18 is a front elevational view of FIG. 17;

FIG. 19 is a rear elevational view of FIG. 17;

FIG. 20 is a left side elevational view of FIG. 17;

FIG. 21 is a right side elevational view of FIG. 17;

FIG. 22 is a top elevational view of FIG. 17;

FIG. 23 is a bottom elevational view of FIG. 17;

FIG. 24 is another perspective view of FIG. 17;

(Continued)

FIG. 25 is a perspective view of a fourth embodiment of an LED light showing our new design;
 FIG. 26 is a front elevational view of FIG. 25;
 FIG. 27 is a rear elevational view of FIG. 25;
 FIG. 28 is a left side elevational view of FIG. 25;
 FIG. 29 is a right side elevational view of FIG. 25;
 FIG. 30 is a top elevational view of FIG. 25;
 FIG. 31 is a bottom elevational view of FIG. 25; and,
 FIG. 32 is another perspective view of FIG. 25.
